UNITED STATES PATENT OFFICE.

WALTER H. WAKEFIELD, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

THREAD CUTTER FOR WEFT-REPLENISHING LOOMS.

Application filed December 27, 1926. Serial No. 157,091.

This invention relates to thread cutters for weft replenishing mechanisms more particularly though not necessarily, of the multi-color type, and it is the principal object of 5 the invention to provide a thread cutter which is both open and closed positively without the use of springs and without contact with the lay to open the cutter.

Most weft replenishing mechanisms are 10 provided with a shuttle feeler the purpose of which is to arrest transfer when a shuttle is so widely misplaced as not to be able to receive the incoming bobbin properly. It has been proposed heretofore to mount the thread 15 cutter on the shuttle feelers but in many instances where this is done it is found that the cutter is opened before the shuttle arrives in position to be actuated by the feeler and if the feeler should be raised by a misplaced 20 shuttle the cutter operates, even though a transfer does not take place. This is particularly true where the shuttle is only slightly misplaced and the cutter as a result lies behind the front wall of the shuttle in position 25 to receive the weft. As the transfer is revoked the same bobbin will be active on the next pick and inasmuch as the thread has been cut the loom will be stopped by the filling fork. It is an important object of my 30 present invention to provide a thread cutter which shall be controlled by the transferrer mechanism but not dependent in any way for its cutting stroke upon said mechanism, to the end that when a shuttle is misplaced on 35 the transferring beat of the loom the cutter will not close while in cutting position.

In copending application Serial #154,808 filed by Hook there is shown a cutter wherein in the first part of the downward movement 40 of the transferrer arm releases a spring to operate the cutter. In my present invention I employ the transferrer arm to release the cutter but the actual closing does not occur until the lay nears front center, thus 45 giving the cutter more time to receive the thread to be cut. If transfer is revoked the cutter will close as the shuttle feeler is raised but the closing will be at a slow rate and the thread will have time to fall out of 50 the space between the cutter blades as they move upwardly about the axis of the shuttle feeler.

It is a further object of the invention to provide a cutter on the shuttle feeler closed

by the lay but having the lay engaging part 55 of the cutter offset from the shuttle engaging part of the feeler so that a slightly misplaced shuttle will raise the feeler but will not engage the offset of the cutter, thus permitting the cutter to rise without cutting.

With these and other objects which will appear as the description proceeds, my invention relates to the arrangements and combinations of parts hereinafter set forth, and more particularly pointed out in the claims.

In the accompanying drawings, wherein a convenient embodiment of my invention is shown,

Fig. 1 is an elevation of a portion of a multi-color weft replenishing mechanism as viewed from the interior of the loom and having my invention applied thereto,

Figs. 2, 3 and 4 are detail operating views similar to a portion of Fig. 1 and showing the mechanism in different positions, and

Fig. 5 is a horizontal section on line 5—5 of Fig. 3 but with the shuttle and lay advanced to a position under the cutter and with the shuttle slightly misplaced so as to revoke the transfer without operating the cutter.

Referring to the drawings I have shown a loom frame 10 on which is mounted the stand 11 of a weft replenishing mechanism indicated generally at 12. A stud 13 mounted on the stand 11 affords pivotal support for a transferrer arm 14 having a portion 15 which moves in an arcuate slot 16. Vertical slides 17 may be employed to control the release of the bobbins and a shuttle feeler holder 18 is pivoted as at 19 to the magazine. A rod 20 connected as at 21 to the feeler holder extends upwardly to the top shaft of the replenishing mechanism 12 and acts to depress the holder 18 just prior to transfer.

A shuttle feeler 22 is secured in the holder by means of a screw or bolt 23 and has a forwardly and downwardly inclined edge 24 positioned to be engaged either by a misplaced shuttle or the back of the box. The lay L may have a box back 25 which positions the shuttle S. The replenishing mechanism described may be substantially the same as that set forth in Patent No. 1,030,748 to Ryon and the shuttle feeler supported on the holder 18 may be the same as that shown in Patent No. 1,022,108 to Ryon. It is sufficient for the present purposes to state that when a trans-

fer is about to take place the shuttle feeler 22 will be moved downwardly from the position shown in Fig. 1 to that shown in Fig. 2 and that the transferrer arm 14 will descend by 5 connections not shown but well understood to insert a new bobbin in the shuttle. If the shuttle should be improperly placed, however, the shuttle feeler 22 will be raised and by means of mechanism not shown but 10 set forth in the aforesaid patents to Ryon, the transferrer arm will be prevented from descending and will remain in the position shown in Fig. 1.

My invention relates more particularly to 15 a cutter to be mounted on the shuttle feeler and while I do not wish to be limited to any particular form of cutter yet for the purposes of illustration I have shown a thread cutting device somewhat similar to that 20 shown in co-pending application No. 127,695 filed by Chevrette. Accordingly, in carrying out my invention I provide the bottom of the shuttle feeler with a cutting edge 40 stationary with respect to the feeler 22 and 25 pivot a movable cutter blade 41 on said feeler as at 42. A thread clamp 43 is secured to the shuttle feeler as at 44 and presses the movable blade 41 against the fixed blade 40 and cooperates with the movable blade to 30 clamp the filling extending between the selvage of the cloth and the cutter 41.

The movable blade has an arm 45 having a 35 pin 46 which enters slot 47 in the lower end of an upwardly extending connector 48. Said connector is attached as at 49 to a small bell crank lever 50 pivoted as at 51 to the stand of the replenishing mechanism 12. One arm 52 of said lever cooperates with a 40 fixed stop 53 to limit counterclockwise movement of the lever 50 and the other arm 54 extends downwardly and normally has holding engagement with a movable stop 55 secured to the transferrer arm 14.

As shown more particularly in Fig. 5 there 45 is formed preferably integrally with the blade 41 an actuating arm 56 offset from the blade 41 and extending inwardly toward the selvage, said arm having a rounded end 57 to cooperate with the shuttle box back 25 of 50 the lay L.

Under normal conditions the parts are in 55 the position shown in Fig. 1 and when a transfer is about to take place the shuttle feeler will be moved downwardly by rod 20 to the position shown in Fig. 2. Inasmuch as the transferrer arm is up at this time, stop 55 will be in engagement with arm 54 and as pin 46 moves down with the feeler it will engage the bottom of slot 47 and be held 60 against further downward movement, thus opening the cutter as shown in Fig. 2. If the shuttle be properly placed the transferrer arm 14 will descend and the stop 55 will move away from the arm 54 so that the cutter 65 is free to move about stud 42 in a clock-

wise direction but will remain open a short interval of time. As the lay advances the back of the box 25 will engage the cam part 57 of arm 56 and move the same upwardly as shown in Fig. 4, completing the cutting 70 movement while the lay L is still a short distance from front center. As the lay continues to move to its extreme forward position the transferrer arm 14 will continue downwardly and the back of the box will 75 engage the inclined surface 24 of the shuttle feeler 22 to lift the same and restore it to the normal position shown in Fig. 1.

During this restoration pin 46 will move 80 upwardly in slot 47 and upon reaching the top of said slot will raise arm 52 against fixed stop 53, stop 58 on the shuttle feeler holding the movable cutter to cause pin 46 to rock lever 50. At a slightly later time in the pick 85 the transferrer arm 14 will move upwardly to the position shown in Figs. 1 and 2 and the pin or stop 55 will engage the arm 54 to hold the parts in the position shown in Fig. 1.

Should the shuttle be improperly boxed, as 90 indicated in Fig. 5, with the nose N thereof located nearer the selvage than usual the inclined surface 24 will be raised before the transferrer arm 14 has time to start its downward movement and the arm 56, being offset from the shuttle feeler, will be out of position with respect to the shuttle and will not 95 be moved angularly relatively to the shuttle feeler as the latter starts to move upwardly. The cutter blade 41 will therefore remain in the open position shown in Fig. 2 until the 100 pin 46 reaches the top of the slot 47 at which time the jaw 41 will be inclined at such an angle that the filling F will fall from between the cutters before the blade 41 is reset to the normal position shown in Fig. 1. At the 105 time of closing of the cutter under the conditions just described the same will be above the shuttle so that the tension of the filling will tend to move the same downwardly out of the notch defined between the cutters.

From the foregoing it will be seen that I 110 have provided a thread cutter for a weft replenishing loom wherein the opening of the cutter depends upon the position of the trans- 115 ferrer arm and wherein the cutter is opened at the time the shuttle feeler 22 moves downwardly. It will further be seen that even though the shuttle feeler may engage an im- 120 properly placed shuttle the cutter will be closed not on the first part of the revoking movement of the shuttle feeler as is customary, but as the revoking movement is being completed, so that the filling extending 125 from the selvage to the bobbin in the shuttle will be left intact and not cut as is the case with most cutters mounted on shuttle feelers. The thread falls out of the notch between the two cutters largely because of the location 130 of the center 19, the notch between said cut-

ters opening downwardly as the shuttle feeler 22 swings upwardly. Furthermore, the actuator for the movable cutter is offset so as not to be engaged by a slightly misplaced 5 shuttle.

Having thus described my invention it will be apparent that changes and modifications may be made therein by those skilled in the art without departing from the spirit and 10 scope of the invention, and I do not wish to be limited to the details herein disclosed, but what I claim is:

1. In a filling thread cutter for looms, a transferrer arm, a lay, a shuttle feeler to be 15 moved to shuttle feeling position prior to the movement of the transferrer arm, a thread cutting mechanism mounted on the shuttle feeler, means including a connection with the transferrer arm to open the cutter as the 20 shuttle feeler moves to shuttle feeling position and the transferrer arm is raised, and means operated by the lay to close the cutter positively while the shuttle feeler is in feeling position and the transferrer arm has 25 started a transferring movement to break said connection.

2. In a filling thread cutter for a loom having a lay, a transferrer arm normally raised and in inoperative position, a shuttle feeler 30 normally raised and movable toward shuttle feeling position prior to transfer, a cutter mounted on the shuttle feeler and normally closed, means including a connection with the transferrer arm when the latter is raised to 35 open the cutter when the shuttle feeler moves to feeling position, and means to be engaged by the lay to close the cutter when the shuttle feeler is in feeling position and the transferrer arm has started on a transfer move- 40 ment to break said connection.

3. In a thread cutter for a loom having a

lay, a transferrer arm normally inoperative, a shuttle feeler normally inoperative but movable to shuttle feeling position prior to the time of transfer, a thread cutter on the 45 shuttle feeler normally closed, connections for the cutter established when the transferrer is inoperative to open said cutter when the shuttle feeler moves to shuttle feeling position, said connections preventing the closing of the cutter while the shuttle feeler is in shuttle feeling position if the transferrer arm remains inoperative, and means engageable by the lay to close the cutter when the 50 shuttle feeler is in feeling position and the 55 transferrer arm has moved from inoperative position to disestablish said connections.

4. In filling thread cutting mechanism for a loom having a lay, transfer mechanism, shuttle feeling mechanism to prevent operation of the transfer mechanism when a shuttle is slightly misplaced, cutter mechanism mounted on the shuttle feeler normally closed and open when the shuttle feeler moves to shuttle feeling position, and means operatively connected to the cutter and offset from the shuttle feeler in the direction of the length of the shuttle to be out of the range of a slightly misplaced shuttle, 60 said means closing the cutter by engagement 65 with the lay when the shuttle feeler is not engaged by a misplaced shuttle, and said means moving with the shuttle feeler without relative movement with respect thereto and out of engagement with the lay and misplaced shuttle so that the cutter remains open 70 while the shuttle feeler starts away from shuttle feeling position when the shuttle feeler is moved by a misplaced shuttle. 75

In testimony whereof I have hereunto affixed my signature.

WALTER H. WAKEFIELD.
